ATTYS.

UNITED STATES PATENT OFFICE.

HENRY K. SANDELL, OF CHICAGO, ILLINOIS, ASSIGNOR TO MILLS NOVELTY COMPANY, OF CHICAGO, ILLINOIS, A CORPORATION OF ILLINOIS.

SLOT-PROTECTOR FOR SLUG-OPERATED MACHINES.

No. 907,581.

Specification of Letters Patent.

Patented Dec. 22, 1908.

Application filed November 27, 1907. Serial No. 404,045.

To all whom it may concern:

Be it known that I, HENRY K. SANDELL, a citizen of the United States, residing at Chicago, in the county of Cook and State of Illinois, have invented a new and useful Improvement in Slot-Protectors for Slug-Operated Machines, of which the following is a specification.

The object of my invention is to provide a novel construction of device for preventing the use of any other than a particular form of slug as a means for primarily actuating the mechanism of a slug-operated vending or other machine.

In the accompanying drawing, Figure 1 shows my improved device by a broken view in side elevation with the particular shape of slug for use therewith in full lines near the entrance to the chute and by dotted lines inserted into the same, and Fig. 2 shows the device in front elevation regarded in the direction of the arrow on line 2, Fig. 1.

The device may be applied to the front wall, represented at 3, of any of the varieties of machine to be protected against the use of spurious slugs. It consists of a chute 4 supported in inclined position on a plate 5 adapted to be fastened to the face of the wall 3 at an opening 6 therein through which the lower end of the chute protrudes into the machine-casing; a chamber or housing 7 extending laterally from the outer end of the chute and having journaled in it a toothed wheel 8 of general star-shape, the teeth of which extend from the chamber into the path through the chute near its insertion-end, and a pair of pins 9, 9 extending across the path through the chute near its lower side adjacent to the wheel 8, forming a slug-insertion space between the pins and the wheel. The slug required for coöperation with my improved device is represented at 10. It is of general star-shape and consists of a disk provided with radial teeth. The diameter of the slug or token 10 is such as to adapt it to be inserted into the mouth of the chute and encounter with one tooth a tooth of the wheel and with another tooth the outermost pin 9. The gravity of the token causes it to work its passage through the space between the wheel and pins by meshing with the wheel-teeth to

rotate the wheel and with the pins 9, which afford stationary bearings from which to enable the slug to roll against the wheel-teeth for turning the wheel.

While the space in the chute between the teeth protruding into it from the wheel 8 and the pins 9 permits the insertion into the chute of a spurious token small enough to clear said teeth and pins, the weight of such small token would be insufficient to operate the machine and its use, therefore, would not avail the purpose of the user thereof; and no larger token, unless it be of, or approximately of, the shape and size represented, could be used, since the wheel 8 and outer pin 9 would arrest it in the insertion-end of the chute, and the likelihood of persons making tokens like the token 10 for spurious use on machines equipped with my improved device is so remote as to render it a desirable protection.

What I claim as new and desire to secure by Letters Patent is:

1. A slug-insertion-slot protector for slug-operated slot-machines, comprising a chute extending in position to feed slugs through it by gravity, a housing extending laterally from the outer end of the chute, a toothed wheel journaled in said housing to protrude into the path through the chute, and a pin crossing the chute adjacent to the wheel at the opposite side of said path and forming with said wheel a passage between them for a toothed-disk form of slug and adapted to turn such a slug by its encounter therewith into engagement with said wheel.

2. A slot-protector of the character described, comprising a chute, a housing extending from the outer end of the chute, a toothed wheel journaled in said housing to protrude into the chute at one side of the path through it, and a pair of pins crossing the chute adjacent to the wheel near the opposite side of said path and forming with the wheel a passage for a toothed-disk form of slug, for the purpose set forth.

HENRY K. SANDELL.
